ADOLPH LOWY, OF NEW YORK, N. Y.

AUTOMOBILE TRUNK.

Application filed August 10, 1927. Serial No. 211,989.

The present invention relates to improvements in trunks, designed particularly for use on motor cars.

Trunks of the type mentioned are usually mounted on a shelf or bracket upon the rear end of motor vehicles, and are usually in the form of an ordinary trunk with the exception that they are narrower so as not to occupy too much space. These trunks are usually provided with a hinged lid or cover, and it is for this reason that access cannot be easily had to the interior of the same, attention being called to the fact that the shelf or brackets above referred to are usually disposed at some distance above the rear bumpers of the motor vehicle. In practice it has been found that, in order to remove an object or article from the trunk, it is often necessary to step on the rear bumper of the motor car.

The main object of the present invention is to so construct the trunk that easy access can be had to the interior thereof without being compelled to step onto the rear bumper of the car or without making use of a ladder.

Another object of the invention is to so construct the trunk that it contains a plurality of compartments, some of which are adapted to receive suit cases, traveling bags and the like, and the others of which house drawers, all compartments being conveniently accessible, and some of said drawers being concealed from view and held within their compartments by the hinged ends of the trunk and other drawers being provided with means co-operating with means on said hinged ends for holding the latter in their closing positions.

A further object of the invention is to provide a trunk of the character specified which is simple in construction, efficient in operation, durable in use and capable of manufacture on a commercial scale, or in other words one which is not so difficult to make as to be beyond the reasonable cost of such a contrivance.

A still further object of the invention is to so design the trunk that the opening and closing of its hinged ends is not interfered with by the usual accessories mounted upon the motor car chassis and body.

With these and other objects in view, which will more fully appear as the nature of the invention is better understood, the

same consists in the combination, arrangement and construction of parts hereinafter described, pointed out in the appended claim and illustrated in the accompanying drawings, it being understood that many changes may be made in the size and proportion of the several parts and details of construction within the scope of the appended claim, without departing from the spirit or sacrificing any of the advantages of the invention.

One of the many possible embodiments of the invention is illustrated in the accompanying drawings, in which:—

Figure 1 is a central vertical longitudinal section taken through a trunk constructed in accordance with the present invention; Fig. 2 is an end view thereof; Fig. 3 is a front view of the same, one of the hinged ends of the trunk being shown in open position; and Fig. 4 is a section taken on line 4—4 of Fig. 2, on a larger scale.

In the drawings, the numeral 10 indicates the body portion of the trunk which is in the form of an oblong rectangular casing comprising a bottom 11, side walls 12 and a top 13. The casing may be made of any suitable material, for instance wood, covered by leather or like material, not shown, and its elements may be united in any preferred manner. The ends of the trunk are hinged at 15 to the top 13 and are each provided along their longitudinal edges with flanges 16, which overlap the vertical edges of the sides of the casing, as clearly shown in Figs. 3 and 4 of the drawings. The ends are shorter than the heights of the side walls, for a purpose hereinafter to be described. The interior of the casing thus constructed is divided by a transverse vertical partition 17 into compartments 18 and 19, the partition being placed close to one of the trunk ends so that one of the said compartments is considerably larger than the other one. In the compartment 18 is formed a shelf 20, onto which may be placed one or more traveling bags or suit cases 21 and the like, and below the said shelf is slidably arranged a drawer 22. The compartment 19, on the other hand, is provided with a plurality of shelves 23, on each of which is slidably arranged a drawer 24. The lowermost shelf 23 is disposed in alignment with the shelf 20 above referred to, and below the same is slidably arranged a drawer 24'. The ends 14 of the trunk extend, when in their closing

105
110

positions, below the shelf 20 and the lowermost shelf 23, respectively, as clearly shown in the several figures of the drawings.

Below the shelf 20 and lowermost shelf 23 are provided in each side 12 of the trunk apertures 25, in alignment with apertures 26 in the drawers 22 and 24', respectively, and into each set of registering apertures is adapted to be fitted a locking pin 27, provided with a suitable means by which said locking pins may be disengaged from the trunk and the drawers mentioned. These means may be of any suitable construction. In the case illustrated, it is in the form of a leather flap 28, the said flaps and locking pins being concealed from view by the flanges of the trunk ends when the latter are in their closing positions. In order to hold these trunk ends in closing positions, key-operated locking means are provided, each locking means consisting of two elements, denoted by the numerals 29 and 30, the elements 29 being fastened in any suitable manner to the trunk ends and the elements 30 being mounted upon the drawers 22 and 24'. In addition to this, each flange 16 carries a latch member 31 for co-operation with a latch member 32 on one of the sides 12 of the trunk body.

In order to hold the trunk ends in their open positions when swung around their hinges, brackets 33 are pivoted at 34 to the outer faces of the trunk sides 12. When the said brackets are swung outwardly to the positions shown in Fig. 3 of the drawings, they form supports for the trunk ends. The brackets are adapted to swing inwardly against the outer faces of the trunk sides and are concealed from view by the flanges 16 of the trunk ends, when the latter are swung to closing positions.

In Fig. 1 of the drawings, the trunk is illustrated in its closed position, in which the locking pins 27 prevent withdrawal of the drawers 22 and 24'. The trunk ends are thus prevented from being swung around their hinges 15 toward opening positions, the co-operating locking means 29 and 30 being prevented from disengagement by key-operated locking mechanisms. If access is to be had to the compartment 18 of the trunk, the respective trunk end 14 is swung around its hinge 15, after the latch members and

the lock members have been disengaged, and supported by the respective brackets 33 in horizontal position in the plane of the trunk top. The drawer 22 may then be withdrawn after first disengaging the locking pins thereof from the trunk sides and the said drawer. If any one of the drawers 23 is to be removed from the trunk, the trunk end co-operating with the same is shifted into the position shown at the right-hand side of Fig. 3 of the drawings, whereby all drawers may be withdrawn with the exception of the drawer 24', which may be removed only after its locking pins are disengaged therefrom and from the trunk sides.

It is to be noted that there is nothing on the car body or car chassis which interferes with the opening and closing of the trunk ends, and it is also to be observed that access may be had to the trunk compartments while the user stands on the ground, in contradistinction to the trunks heretofore in use, in which, after the trunk cover or lid has been swung to open position, the user has to stand either on the rear bumpers of the car or on some high object in order to reach the articles within the trunk compartments. It will be seen from the foregoing that the invention herein described is of simple construction, compact and is adapted to be mounted on automobiles of any type.

What I claim is:—

An automobile trunk comprising a casing consisting of a bottom, side walls and a top, two drawers on said bottom slidable in opposite directions, a trunk end hinged to each free edge of said top adapted to engage the casing, each trunk end extending below the top of one of said drawers when in engagement with said casing sides, means for fixing said drawers against movement in said casing, locking means for securing said casing ends to said drawers, and flanges along the vertical edges of said casing ends adapted to abut against the outer faces of said casing sides, said flanges concealing from view said drawer fixing means when said casing ends engage said casing sides.

Signed at New York, in the county of New York, and State of New York, this 20th day of June, A. D. 1927.

ADOLPH LOWY.
